Patented July 15, 1924.

1,501,580

UNITED STATES PATENT OFFICE.

ROBERT BEAM, OF KALAMAZOO, MICHIGAN, ASSIGNOR TO H. M. LOWE, OF BATTLE CREEK, MICHIGAN.

CRUTCH.

Application filed October 13, 1921. Serial No. 507,564.

To all whom it may concern:

Be it known that I, ROBERT BEAM, a citizen of the United States, residing at Kalamazoo, in the county of Kalamazoo and State of Michigan, have invented certain new and useful Improvements in Crutches, of which the following is a specification.

The present invention more particularly relates to crutches capable of adjustment, 10 wherein the length between extremities as well as adjustment of the handles may be readily accomplished.

Among other objects the invention contemplates making the side standards telescopically adjustable, whereby the desired length may be easily attained; whereby the handle may be regulated to suit the requirement of the user; whereby in making adjustment for either the handle or the side standards there will be no weakening of the parts; and whereby the crutch will be comparatively simple, neat in appearance and substantial. To the foregoing ends my invention consists in the combination and arrangements of parts, as will be hereinafter more fully set forth, shown in the accompanying drawings and defined in the appended claims.

Referring to the drawing aforesaid, Figure 1 is a broken side elevation partly in section of my improved crutch showing the parts in locked operative engagement.

Fig. 2 is a broken section of the crutch on the line α of Fig. 1, but with the clamping lever elevated in the manner of releasing the binding of the parts.

Fig. 3 is a detail section longitudinally of the handle, a cross section through the telescopic side standards at the handle intermediate section with the clamping lever in position for releasing the binding of the parts.

Fig. 4 is a perspective view of an intermediate clamping band.

Fig. 5 is a perspective view of a forked clamping member.

Like marks of reference refer to corresponding or equivalent parts in the different views, in which A represents forked tubular uprights of a central standard or leg 1, the uprights being disposed substantially parallel, of uniform length, and each having a longitudinal slit 2 extending from its free end to a point somewhat below a handle B interposed between said uprights, said slits 55 preferably being disposed transverse to a plane of the forked sides.

Adapted to fittingly slide in the open free ends of the forked sides A, tubular extension sides C are placed. These extensions at their tops are fitted with a customary arm-supporting curve 3, the arrangement of the parts being such that the space between the free ends of the forked sides A and the arm support 3 will permit of sufficient adjustment to meet all ordinary requirements for the purpose designed.

Fitted over each of the side standards A, forked clamping members 4 are placed, the forks of said members having aligned holes adapted to nicely fit on said standards when the parts are in operative position, the intermediate portion of a member forming an offset 5 with a central hole 6. Between the forks of the clamping members 4, intermediate clamping bands 7 are placed. These bands are formed to nicely slide on the side standards A, and when in operative position a stem 8 projects through the hole 6 in the offset 5 of the member 4. The outer ends of the stems 8 are screw-threaded, one of the stems being right the other left handed, and each adapted to be received by correspondingly screw-threaded openings in the ends of a U-shaped clamping lever D and also correspondingly screw-threaded openings in the handle B, as shown.

The arrangement of the parts is such that when the clamping lever D is elevated, as shown in Figs. 2 and 3, a relaxing of the binding parts is effected, permitting the standards C to be telescopically moved either in or out on the standards A, and also permitting the handle B together with all its connective members to be moved along the side standards to accommodate any adjustment required of the crutch, a downward movement of the lever D forcing the clamping bands 7 outward, and through the medium of the slotted standards A causing said standards to slightly collapse and impress the standards C, and at the same time disrupting the alignment of the tubes through the eyelets of the forked members 4 and the clamping bands 7, most effectively preventing any loosening or sliding of the parts thus bound.

The adjustment of the parts having been effected, the handle B is turned sufficiently on the threaded stems 8 to bring the ends of said handle snugly against the ends of the lever D to effect an unbroken and smooth appearance of the assembled parts, sufficient

resiliency in the parallel side standards permitting such operation to be easily effected.

In assembling parts the clamping bands 7 are placed between the forked eyelets of 5 the members 4 in proper position, thence the clamping member D and handle B are properly screwed to place, after which the assemblage is placed with the aligned eyelets of the members 4 and 7 about the side standards 10 A, the arm-supporting standards C being then placed within the slotted standards A and the parts locked, as occasion may require.

A crutch made of aluminum or a combination 15 of metal and wood is comparatively light, thoroughly stable, and made to one general specification will fulfil the purpose for which a crutch is ordinarily used and also any requirements which may arise, in 20 the great majority of cases.

From the foregoing description taken in connection with the drawing it is believed that the operation and advantages of my improved crutch will be fully comprehended.

Having, therefore, set forth my invention, what I claim as new and desire to secure by Letters Patent, is:—

1. A crutch, the combination with oppositely-disposed side members, of a forked 30 yoke having aligned openings fitted about each of said side members, a clamping member fitted about each of said side members between the aligned openings of said yokes and having threaded shanks extending 35 through free openings in offset portions of said forked yokes, a U-shaped clamping lever having aligned threaded apertures in its ends fitted on to said threaded shanks, and a handle having threaded apertures in its 40 ends adapted to thread onto said threaded shanks between the ends of said U-shaped clamping lever, substantially as specified and for the purpose set forth.

2. A crutch, the combination with oppositely-disposed side members, of a forked 45 yoke having aligned openings fitted about each of said side members, a clamping member fitted about each of said side members between the aligned openings of said yokes and having threaded shanks extending from 50 said clamping members through free openings in offset portions of said forked yokes, one of said shanks having a right and the other a left handed screw thread, a U-shaped

clamping lever having aligned right and left 55 handed screw-threaded openings at its ends fitted onto the screw-threaded shanks of said clamping members and a handle interposed between the ends of said clamping lever and having one right and one left handed screw-threaded aperture adapted to receive a correspondingly-fitted end of the screw-threaded shanks of said clamping members, substantially as and for the purpose set forth.

3. A crutch, the combination of forked 60 tubular sides having a slit in each side opening at its end and on a side transverse to a plane through said fork, an arm-support having side extensions adapted to telescope within said forked sides, a handle interposed between said forked sides, yokes having aligned openings fitted about said forked sides at each end of said handle, clamping members between the aligned openings of 65 said yokes and having threaded shanks, said threaded shanks extending through apertures in offset portions of said yokes, a U-shaped clamping lever having aligned openings in its ends threaded onto the threaded shanks of said clamping members, said handle having threaded apertures in its ends 70 adapted to screw onto the ends of said threaded shanks between the ends of said clamping lever, to be operated substantially as and in the manner specified and for the 75 purposes set forth.

4. In a crutch, the combination with oppositely-disposed slidably fitted side portions, of forked members having aligned 80 openings enclosing said slidably-fitted side portions, each of said forked members having an offset with a centrally-disposed opening, clamping bands encompassing said slidably-fitted side portions intermediate the forks of said members and having stems through the openings of said offsets, a handle adapted to receive the ends of said stems, and means interposed between said handle and said offsets on said stems whereby said handle may be adjustably fitted between said 85 forked members and whereby said slidably-fitted side portions may be adjusted as expedient.

ROBERT BEAM.
